UNITED STATES PATENT OFFICE

2,571,527

CAST CUTTER

Martin Boyer, Lowry, Minn., assignor of one-third
to Birth A. McIver, Lowry, Minn.

Application October 15, 1947, Serial No. 779,956

2 Claims. (Cl. 30—167)

1

This invention appertains to novel and useful improvements in implements utilized for specific purposes and relates particularly to a device for cutting a cast normally used in association with certain injuries.

An object of this invention is to simply and easily cut a cast.

Another purpose of this invention is to provide means for cutting a cast axially thereof.

Another object of this invention is to provide improved means for protecting the pertinent portion of the anatomy during the cutting operation.

Another purpose of this invention is to provide a guard adjacent the cutting means used in the present invention.

Another purpose of this invention is to provide means for adjusting the above mentioned protecting means.

A still further object of this invention is to provide lubricant receiving passages to insure high efficiency and to deter friction.

Ancillary objects and features of novelty will become apparent to those skilled in the art, and following the description of the preferred form of the invention, illustrated in the accompanying drawing, wherein:

Figure 1 is an elevational side view of the preferred form of the invention;

Figure 2 is a plan view of the invention shown in Figure 1;

Figure 3 is a perspective view of a portion of the frame, illustrating particularly the bifurcations thereof and the bearing block utilized in association therewith;

Figure 4 is a perspective view of the shaft to be placed in the bore of the bearing block, and;

Figure 5 is a perspective view of the guard used for protecting the anatomy during the cutting operations.

Referring now in detail to the illustrated preferred form of the invention, reference is made primarily to Figure 2 and Figure 1 wherein the frame member 16 is disposed with a suitable handle 12 integral therewith and forming a portion thereof. The end opposite the said handle 12 is bifurcated, the bifurcations 14 and 16 composing this construction.

The ends of the said bifurcations 14 and 16 are again bifurcated as seen in Figure 3, and as indicated at 18 and 20, 22 and 24 to form bearing block receiving members. A bearing block 26 is positioned within the said bifurcations 18, 20, 22 and 24 and a bore 28 extends therethrough.

A shaft 30 is positioned in the said bore 28 and has threads at one terminal portion thereof. A

2

pair of nuts 32 and 34 respectively or the equivalents carry means which is supplied on the said threaded portion of the shaft 30 for receiving a cutting disk 36 therebetween. This cutting disk 36 has teeth about the periphery thereof for engagement with a cast. Means for lubricating the said shaft 30 is provided. This means may be seen as the passages 38 and 40 respectively provided in the said bearing block 26, the passages 10 communicating with the said bore 28. Obviously, any suitable lubricant may be supplied in the said passages thereby deterring or inhibiting friction to a substantial degree.

An arcuate rod 42 is secured to the said frame 15 10 and has a baffle 44 associated therewith. This baffle is obviously used for the purpose of deflecting cut material and for protection of the operator of the invention.

A slot 46 is also provided in the said frame 10 20 for the purpose of receiving an arm 48 therein. This arm 48 has a plurality of apertures 50 therein which are selectively positionable in alignment with a bore 52, communicating with the said slot 46. A pin or the like 54 may be extended through 25 the said bore 52 and through a selected aperture 50, thereby adjusting the effective length of the said arm 48. A guard 56 may be rigidly secured to the said arm 48, said guard being engageable with a portion of the anatomy beneath the cast 30 to be cut. Of course, by adjusting the arm 48, the distance between the bottom portion of the cutter 36 and the upper surface of the said guard 56 may be regulated in accordance with the thickness of cast to be cut.

To assist in retaining the said shaft 30 in the said bore 28, a thrust bearing 58 may be supplied opposite the said nuts and a suitable set screw or the like may be used in association therewith for retention purposes. The operation of the invention is deemed quite apparent. The cast to be cut is simply held firmly and the guard 56 inserted thereunder. The handle 12 is then grasped and the device urged forward, thereby rotating the cutter 36 and making an incision 45 in the said cast. The guard 56 protects the anatomy of the individual during this cutting operation and the baffle 44 may be employed for parting the cast after the cast has been cut.

Casts of varying thicknesses may be efficaciously cut by use of the present invention, by simple manipulation of the pin 54 as described above.

Due to the extreme simplicity achieved by the present invention a further description thereof is deemed unnecessary. However, it is appar-

ent that variations may be made without departing from the spirit of the invention.

Having described the invention, what is claimed as new is:

1. A cast cutter comprising a frame, said frame formed with a handle at one end thereof and having planar furcations at its other end, said furcations forming extensions of said frame, substantially U-shaped bearing block receiving members formed with the outer end portions of the furcations, a bearing block having its ends fitted within the bearing receiving members, the bearing block being provided with a bore, a shaft disposed in said bore, a freely rotating cutting means secured to one end of said shaft and being rotatably responsive to movement over the cast, a guard provided below said cutting means and adjustably secured to the frame, and a baffle secured to said frame substantially opposite said guard and above said cutting means.

2. A cast cutter comprising a frame, said frame formed with a handle at one end thereof and having planar furcations at its other end, said furcations forming extensions of said frame, substantially U-shaped bearing block receiving members formed at the outer end portions of the furcations, a bearing block having

5 its ends fitted within the bearing receiving members, the bearing block being provided with a bore, said bore extending transversely of the frame, a shaft disposed in said bore, cutting means secured to one end of said shaft, a guard provided below said cutting means and adjustably secured to the frame, a baffle disposed opposite said guard above said cutting means, said frame having an opening therein intermediate its ends, 10 an arm secured to said guard with a plurality of apertures therein, said arm being passed through said opening, and a pin carried by said frame and disposed in a selected one of said apertures to thereby adjustably support said guard.

15 MARTIN BOYER.
